DESIGN FOR A COMBINED BROOCH, COMPACT, LIPSTICK, AND COMB

Ruth L. Fisk, New York, N. Y.

Application June 22, 1945, Serial No. 120,251

Term of patent 7 years

(Cl. D86—10)

To all whom it may concern:

Be it known that I, Ruth L. Fisk, a citizen of the United States of America, residing in New York, county of New York, and State of New York, have invented a new, original, and ornamental Design for a Combined Brooch, Compact, Lipstick, and Comb, of which the following is a specification, reference being had to the accompanying drawing, forming part thereof.

Fig. 1 is a plan view of a combined brooch, compact, lipstick, and comb, showing my new design.

Fig. 2 is an edge view thereof.

Fig. 3 is a plan view in open position, illustrating the compact, lipstick, and comb.

The dominant features of the design reside in the portions shown in full lines.

I claim:

The ornamental design for a combined brooch, compact, lipstick, and comb, substantially as shown and described.

RUTH L. FISK.
